E. L. VAN PELT

FILM JOINING MACHINE

Filed Aug. 30, 1920

Fig. 1.

A technical drawing of a gear assembly. It features two sets of gears: a top set with a 20-tooth gear and a 22-tooth gear, and a bottom set with a 34-tooth gear and a 32-tooth gear. The assembly is mounted on a vertical shaft. Labels include T_1 , T_2 , T_3 , T_4 , B , and F . Dimension lines indicate the pitch diameters of the gears: 62, 42, 35, 34, 32, and 34.

UNITED STATES PATENT OFFICE.

ELMER L. VAN PELT, OF DENVER, COLORADO, ASSIGNOR TO GEORGE FRUTH, OF DENVER, COLORADO, AND HENRY E. McELWAIN, OF HOLYOKE, MASSACHUSETTS.

FILM-JOINING MACHINE.

Application filed August 30, 1920. Serial No. 406,994.

To all whom it may concern:

Be it known that I, ELMER L. VAN PELT, a citizen of the United States, residing at the city and county of Denver, and State of Colorado, have invented certain new and useful Improvements in Film-Joining Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The object of this invention is to provide a mechanical device for joining film strips when assembling or mending the same, whereby the film ends may be properly cemented and pressed together and the waste 20 extremities trimmed off to produce a neat finish at the joint.

Briefly the invention comprises a base carrying at one end an overhanging abraiding member for removing the emulsion from 25 one film strip, a cementing device at an intermediate point of said base, and at the opposite end a trimming press for uniting the superimposed film ends by pressure and trimming off the waste extremities.

30 In the drawings
Fig. 1 is a side elevation of the device;
Fig. 2 is a cross section on line 2—2 of Fig. 1;

35 Fig. 3 is a plan as indicated by line 3—3 of Fig. 1;

Fig. 4 is a cross section on line 4—4 of Fig. 1;

40 Fig. 5 is a view indicating the relation and operation of the cutting and pressing jaws; and

Fig. 6 is a cross section thru the base at the cement reservoir.

The base 10 of the machine is elongated and has at its rear end a foot 12 provided 45 with ears 14 having screw holes for attaching to a support. The sides of the base 10 have guiding grooves 15 extending longitudinally thereof for a purpose to be herein-after described. The rear end of the base 50 is provided with an overhanging head composed of a pair of spaced members 16 separated from the base 10 by a narrow slot 17.

An upper pressing and cutting jaw A is mounted between the members 16 on a pivot 55 18 mounted in said members 16, said jaw

comprising a pressing block 20 to one side of which a specially tempered cutting blade 22 is fixed as by spot welding, the cutting edge being produced by beveling the edge of the blade outward as indicated at 24. To hold said jaw A in elevated or inoperative position, a spring 25 has its upper end secured thereto, its lower end being anchored at 26 to the base. For depressing the jaw A a cam face 27 is provided on the lower end 60 of a handle 28 pivoted between the members 16 of the head by a pivot pin 30.

Immediately below the jaw A, a jaw B is firmly mounted in the base 10, said jaw B being approximately equal to the length of 70 slot 17. The base is cut out to receive the jaw B which comprises a pressing block 32 and a tempered cutting blade 34 spot welded to the block and provided with an outwardly beveled cutting edge 35, like the jaw A. 75 The jaw B is arranged in parallelism with the base and is secured in such position by rivet pins 36 conveniently set in the grooves 15. The jaw A when forced into pressing position is parallel with jaw B. The cutting 80 edges 24 and 35 project beyond the respective blocks 20 and 32 a distance very slightly less than the thickness of the film F. In this manner cutting of the opposed film is avoided and at the same time the 85 brittleness of the film and outward bevel of the cutting edges combine to sever the waste extremities f of the film when the film ends are being pressed between blocks 20 and 32, completely. 90

At the forward end of the machine a foot 40 is provided having at 42 apertured ears for securing to a support, this foot extending under the end of the base 10 and being secured thereto by screws 44. A standard 95 45 rises from the foot and carries a stationary, rearwardly extending arm 46 which has its rear end bifurcated as indicated at 48 to receive an abraiding disc 50 for removal of emulsion from the lower film end. 100 A stepped journaling pin 52 extending thru the rear ends of arm 46 secures said disc in place, the pin 52 being retained by a cotter key 54 in its smaller end. The opposite end of the pin 52 carries a pinion 55 105 for engagement by a rack to be described.

A U-shape carriage 56 extends up both sides of the base 10 and under the bottom thereof, this carriage being slidably mounted on the base by means of longitudinally 110

extending tongues 58 positioned in said guide grooves 15. A standard 60 which rises from the upper edge of one side of the carriage 56 carries an arm 62 which extends 5 forward and carries on its lower edge a rack 64 with which the pinion 55 meshes. The upper edges of the sides of the carriage 56 are substantially flush with the top of the base 10 and are provided with oppositely 10 disposed pairs of film positioning studs 65 adapted to enter the sprocket holes at the edges of the film.

Secured to the under side of one rear end of the stationary arm 46 is a light spring 15 which extends rearward and downward into alinement with the abraiding disc 50 and the pressing faces of blocks 20 and 32, the body of the spring being indicated at 70. At an intermediate point in the base 10 a 20 cement reservoir 74 is provided this being filled if desired with absorbent material 75. The top of the reservoir is closed by a slide plate 76 having an elongated slot 78 extending longitudinally of the base 10 and 25 adapted to receive a cement wiper 80 on the under side of the horizontally arranged free end 82 of the leaf spring 70. The wiper 80 is of approximately the same width as the disc 50 and the pressing portions of the 30 blocks 20 and 32, and it is beveled upward as it extends forward for easy passage of the film.

In using the device, the lower film end is 35 positioned on the studs 65 emulsion side up, and the carriage is moved rearward whereby the rack 64 on the carriage rotates pinion 55 and disc 50 and the emulsion is removed. As rearward movement of the carriage is continued, rack 64 leaves pinion 55 and the 40 film is guided under the inclined portion of spring 70 thereby lifting the same and passing freely along the under side of beveled wiper 80 whereby the emulsion-free area 45 of the film is cemented. Preferably the carriage is stopped and the upper film strip F positioned on studs 65 above the portion 82 of the spring before the film reaches slot 17. Carriage 56 is then moved farther back 50 to bring the film between jaws A and B, the arm 62 passing alongside member 16.

Handle 28 is then depressed whereby the tips f of the film are severed, and the film ends to be joined are firmly pressed together between the opposed parts of blocks 20 and 55 32. Said film ends are maintained in the press a few moments until the cement has acted to complete the joint.

I claim:

1. A film joining machine comprising cutting and pressing means, a cementing device, and a carriage for carrying film from the cementing device to said cutting and pressing means.

2. A film joining machine comprising cutting and pressing members, a cementing de-

vice alined with the cutting and pressing members, and a reciprocable carriage for carrying film from the cementing device to said cutting and pressing means.

3. A film joining machine comprising a 70 pair of relatively movable blocks having opposed faces for pressing film between them, means for applying cement to a film face, said blocks and said means being in longitudinal alinement, and a reciprocating carriage for carrying film past said means to said blocks.

4. A film joining machine comprising a base, a pair of relatively movable blocks on 80 said base having opposed faces for pressing films between them, each block having a cutting edge, and means also on said base to apply cement to a film face.

5. A film joining machine comprising a 85 pair of relatively movable blocks having opposed faces for pressing films between them, means for applying cement to a film face, and means in advance of the cementing means for removing the emulsion from said film face said blocks and said two means 90 being horizontally arranged in longitudinal alinement.

6. A film joining machine comprising a 95 pair of relatively movable blocks having opposed faces for pressing films between them, each block having a cutting edge, means for removing the emulsion from a film face, means for applying cement to said film face said blocks and said two means being in longitudinal alinement, and a reciprocating carriage for carrying film past said 100 two means to said blocks.

7. A film joining machine comprising a 105 pair of relatively movable blocks having opposed pressing faces for receiving films between them, a base by which said blocks are carried, an abraiding member also carried by said base for removing emulsion from a film face, and means also on said base for applying cement to said film face after removal of emulsion.

8. A film joining machine comprising a 110 pair of relatively movable blocks having opposed film pressing faces, and a cutting edge projecting from each face, the cutting edges 115 being offset from each other.

9. A film joining machine comprising a 120 pair of relatively movable blocks having opposed film pressing faces, and a cutting edge projecting from each face toward the other a distance approximating the thickness of a film whereby an end may be cut without cutting an adjacent film, said cutting edges being offset from each other a distance equal to the width of the joint to be produced.

10. A film joining machine comprising a 125 pair of relatively movable blocks having opposed film pressing faces, each face having a cutting edge projecting toward the other face a distance approximating the thickness 130

of a film, said cutting edges being spaced from each other laterally a distance equal to the width of the joint to be produced, and means to apply cement to one of the film faces.

11. A film joining machine comprising a pair of relatively movable blocks having opposed film pressing faces and cutting edges, a base on which said blocks are carried at one end, a rotary emulsion-removing device at the other end of the base, a cementing device between the emulsion remover and the blocks, and a film-carriage movable along the base to carry film past the emulsion remover and the cementing device to the blocks.

12. A film joining machine comprising a base, a pair of relatively movable cutting and pressing blocks on one end of said base, a rotary emulsion-remover mounted on a fixed support at the other end of the base, cementing means between the remover and the blocks, and a carriage slidable along said base having means to position the film to be treated and having a rack operatively connected with the remover to rotate the same as the carriage is moved, said carriage being adapted to carry film past the remover to remove emulsion, past the cementing device to apply cement to the film-face having the emulsion removed, and thence to the cutting and pressing blocks.

13. A film joining machine comprising a horizontally disposed base, cutting and pressing blocks mounted on said base, a cementing device on said base, and a carriage reciprocable on said base to carry film from said cementing device to said blocks.

14. A film joining machine comprising a horizontally disposed base, cutting and pressing blocks mounted on said base, a cementing device on said base and in alignment with said blocks, and a reciprocable carriage to carry film from said cementing device to said blocks.

15. A film joining machine comprising a horizontally disposed base, cutting and pressing blocks mounted on said base, a cementing device on the base, an abraider on said base, said blocks, cementing device and abraider being in longitudinal alignment, and a carriage reciprocable on the base to carry film from the abraider past the cementing device to said blocks.

16. A film joining machine comprising a base, opposed cutting blocks on the base, a cementing device on the base, and a reciprocable carriage to carry film past the cementing device to the cutting blocks.

17. A film joining machine comprising a base, opposed cutting members on the base, a cementing device on the base in alignment with the cutting members, and a carriage on the base to carry film from the cementing device to the cutting members.

18. A film joining machine comprising a base, cutting and pressing blocks thereon, a cementing device on the base, an abraider on the base, said blocks, cementing device and abraider being in longitudinal alignment, and a carriage reciprocable on the base to carry film from the abraider past the cementing device to said blocks.

19. A film joining machine comprising a base, opposed cutting blocks on the base, an abraider, and a carriage on the base to carry film from the abraider to the cutting blocks.

20. A film joining machine comprising a base, opposed cutting and pressing blocks on the base, an abraider, and a carriage to carry film from the abraider to the blocks.

21. A film joining machine comprising a base, opposed cutting blocks on the base, an abraider aligned with the blocks, and a carriage to carry film from the abraider to the blocks.

22. A film joining machine comprising a base, cutting blocks on said base having opposed pressing faces, an abraider aligned with the blocks, means to apply cement, and a carriage to carry film from the abraider to the blocks.

23. A film joining machine comprising a base, opposed cutting blocks on said base, a cementing device and an abraider on said base, and a carriage to carry film from the abraider past the cementing device to the blocks.

24. A film joining machine comprising a base, opposed cutting blocks on said base, a cementing device and an abraider also on said base, said blocks, cementing device and abraider being in longitudinal alignment, and a carriage to carry film from the abraider past the cementing device to the blocks.

25. A film joining machine comprising a base, opposed cutting blocks on said base having opposed pressing faces, a cementing device, an abraider, said blocks, cementing device and abraider being in longitudinal alignment, and a carriage to carry film from the abraider past the cementing device to position between said blocks where the film is trimmed and opposing ends pressed together between the blocks to form the joint.

In testimony whereof I affix my signature.
ELMER L. VAN PEELT.
